UNITED STATES PATENT OFFICE.

FRED J. NUTTING, OF DAYTON, OHIO, ASSIGNOR TO THE NATIONAL CASH REGISTER COMPANY, OF DAYTON, OHIO, A CORPORATION OF OHIO.

CASH-REGISTER.

SPECIFICATION forming part of Letters Patent No. 739,706, dated September 22, 1903.

Application filed August 8, 1898. Serial No. 688,019. (No model.)

To all whom it may concern:

Be it known that I, FRED J. NUTTING, a citizen of the United States, residing at Dayton, in the county of Montgomery and State of Ohio, 5 have invented certain new and useful Improvements in Cash-Registers, of which I declare the following to be a full, clear, and exact description.

This invention relates to improvements in cash-registers, and has more particular relation to improvements in operating devices for the same, and especially for registers of the type patented to H. Cook, No. 464,294, dated December 1, 1891.

15 The primary object of the invention is to provide means for operating a register by utilizing the weight of the operator as the propelling force.

In the appended drawings, forming part of 20 this specification, Figure 1 represents a side elevation, partly in section and partly broken away, of the devices embodying my invention applied to a register of substantially the same construction as that mentioned above. Fig. 25 2 represents a vertical transverse section through the upper portion of my improved operating attachment. Fig. 3 represents a top plan view, partly broken away, of the operating-platform; and Fig. 4 represents an enlarged detail side elevation of a modified form 30 of connection between the platform and the operating devices.

In the said drawings, 1 represents the frame of the cash-register, to which I have shown 35 my invention applied; 2, the power-shaft of the same; 3, the operating-platform; 4, the operating rack-bar, and 5 the release-lever. The register proper shown in the present instance is of substantially the same construction and operation as that described in the aforesaid patent, and attention is therefore called to the latter for a detail description of the parts. The power or revolution shaft 2 of this machine is provided at one end with a 40 gear-wheel 6 and a latch-disk 7, the latter being provided with a peripheral notch or recess 8, into which the end of a locking-pawl 9 is normally drawn by the action of a coil-spring 10. The forward end of said pawl 9 is 45 formed with a notch 11, the upper wall of which is inclined, so that said pawl is oper-

ated to release the disk when a projection 12, mounted on the lever 5, is forced against it by the operation of said lever, the lower wall of said notch contacting with the said projection and preventing overthrow of said pawl. Motion is transmitted to the said gear 6 by a gear-wheel 13, which in turn receives motion from a gear-wheel 14, loose upon a shaft 15, journaled in the frame of the machine. This shaft is also provided with a pinion 16, fast thereon and meshing with the upper portion of the vertical rack 4, so as to receive motion therefrom. Further, said shaft is provided with a stop-disk 17, fast thereon 55 and formed with a stop-shoulder 18, which latter is arranged to be engaged by a pivoted stop-lever 19. This lever is formed with a locking-shoulder 20 and is normally held against the disk 17 by a coil-spring 21, so that 60 said shoulder will engage the shoulder 18, and thus lock the said disk. The locking-lever 19 is arranged to be moved away from the disk 17 to disengage the shoulders and free said disk by a push-bar 22, mounted in suitable 65 guides and connected to the lever 5 by a pivoted link 23. The said locking-disk 17 is provided with a pivoted pawl 24, which engages a ratchet-wheel 25, fast to the gear-wheel 14, whereby the movement of the disk 70 17 in one direction will rotate the wheel 14; but a reverse movement will simply result in the pawl riding over the teeth of the ratchet-wheel. The aforesaid rack-bar 4 receives its motion from the pivoted incline 75 platform 3, to which its lower end is pivoted, and it is held into positive mesh with the wheel 16 at all times by an antifriction-wheel 26, which engages its rear side. The free end of the platform 3 is normally held in an 80 elevated position by a coil-spring 27, secured to said platform, and also to a bracket or yoke 28, which extends over said platform, this upward movement of the platform being limited by an adjustable stop-screw 28^a 85 on the platform and which is arranged to abut against a rigid bracket 29. An approximately triangular-shaped plate 30 is rigidly secured to the lower end of the rack-bar 4 and is provided at one of its lower corners 90 with a pendent piston-rod 31, carrying a piston 31^a at its lower end. This piston is ar-

ranged to operate in a valved cylinder 32, which is supported by two pivoted rods 33, pivoted to opposite sides of the same, so that it may tip from side to side to accommodate itself to the changing positions of the bar 4 and rod 31. In the modified form of connection shown in Fig. 4 the lower end of the rack-bar simply rests upon the platform and is held normally in such contact by a coil-spring 34, connected to said platform, and an eye formed in said bar. This peculiar structure relieves the bar of excessive shock or concussion upon a heavy person stepping upon the platform, as the spring will give under the strain. Excepting this spring attachment the modified form is the same as the form shown in Fig. 1.

The operation of the device is as follows: The operator first steps upon the platform 3, then operates the desired register-keys, and finally operates the lever 5. This last operation releases the mechanism which has been locked by the lever 19 and allows the rack-bar to descend without jar, its movement being cushioned by the air cylinder and piston. The descent of said rack-bar operates the gearing, as before described, and thus rotates the power-shaft 2 one complete revolution. When the operator steps from the platform, the spring 27 draws the same upward to raise the bar 4, the valves in the bottom of the cylinder 32 opening during such operation to allow free movement of the piston. The upward movement of the rack-bar causes a backward rotation of the shaft 15; but this motion is not transmitted to the gear 14, as the pawl 24 rides over the ratchet-wheel 25 when the movement is in this direction. By the peculiar structure of the latch-lever 19 and the disk 17 the weight of the operator is not thrown upon the working parts of the register when the operator steps upon the platform, but upon the said latch-lever. Any suitable casing is arranged about the gearing, rack-bar, latch, &c., for protecting the same, a suitable slot being formed in said casing for the passage of said rack-bar. I do not care to limit the application of my invention to machines of the type shown in the drawings, as the same may be equally well applied to other classes of machines.

Having thus described my invention, what I claim as new, and desire to secure by Letters Patent, is—

- 55 1. The combination with register-actuating devices of a platform for operating said devices, a rack-bar connected to said platform, a train of gears actuated by said rack-bar, a locking-disk connected to said gears, a pivoted spring-pressed lever having a shoulder which is normally forced into engagement with said disk, and a hand-lever and connections for operating said pivoted lever to disengage said shoulder; the lever automatically falling back to locking position when released.
- 60 2. The combination with register-actuating devices, of means for operating said devices

by the weight of the operator, a lock for said operating means an auxiliary lock interposed between the register-operating devices and the operating means and means for simultaneously operating both of the locks. 70

3. In a cash-register, the combination with register-operating devices, of gearing for actuating the same, a platform arranged to receive the weight of the operator, means connecting said platform and gearing, a latch for said gearing, a key for operating said latch, and an adjustable stop for limiting the movement of said platform. 75

4. The combination with register-operating mechanism, of a platform arranged to be actuated by the weight of the operator, actuating devices for the register-operating mechanism engaging said platform so as to be 80 positively actuated in one direction thereby and a spring connecting said platform and devices whereby the latter are operated upon the reverse movement of the platform through the medium of said spring. 85

5. The combination with register-operating mechanism, of operating-gearing for the same, means for actuating said gearing by the weight of the operator, a lock for the operating mechanism, a lock for said gearing and 90 means for simultaneously releasing both of said locks. 95

6. The combination with register-operating devices, of a platform arranged to be actuated by the weight of the operator, operating-gearing connected to said platform, two pivoted locking-levers for different portions of said gearing and means for simultaneously operating said levers to release the gearing. 100

7. The combination with register-operating devices, of a platform arranged to be actuated by the weight of the operator, a spring connecting the platform and operating devices, an air-buffer for controlling the descent of the platform, and a spring for returning the platform to its elevated position. 105

8. The combination with a cash-register, operating-gearing having a rotary movement, an operating mechanism for said gearing including a reciprocating device, a lock for the operating-gearing, a lock for the operating mechanism, means for simultaneously operating the two locks, and a platform for the operator connected to the reciprocating device. 115

9. The combination with a cash-register, operating-gearing having a rotary movement, operating mechanism for said gearing including a reciprocating device, a lock for the operating-gearing, a lock for the operating mechanism, a hand-lever for operating the two locks, and a platform arranged to be actuated by the weight of the operator and connected to the reciprocating device. 125

10. The combination with a cash-register, operating-gearing, a lock for said gearing, an operating mechanism connected to said gearing and including a reciprocating device, a lock for holding said device in one of its ex- 130

treme positions of travel, a platform arranged to receive the operator and connected to the said device, means for converting the reciprocating movements of the operating mechanism into rotary movements for the register-gearing, and means for operating the respective locks.

11. In a cash-register the combination with an operating mechanism, of a motor actuated by the operator's weight, a latch for said motor to receive the stress of the same before it is released, and a broken connection intermediate the latched portion of the motor and the operating mechanism for preventing any shock to the operating mechanism when the motor is arrested.

12. In a cash-register the combination with an operating mechanism, of a platform-motor arranged to be actuated by the weight of the operator, a lock for said motor, arranged to receive the stress of the same prior to its release, and a broken connection intermediate the latched portion of the motor and the operating mechanism for preventing any shock to the operating mechanism when the motor is arrested.

13. The combination with a cash-register, of an operating-gearing for the same, a motor mechanism for actuating said gearing, a lock for said motor mechanism, a lock for said gearing, and means for simultaneously releasing both of the locks.

14. In a cash-register the combination with an operating-gearing for the same, means for actuating said gearing by the weight of the

operator, a lock for the actuating means, a lock for said gearing, means for releasing both of the locks, and devices between the actuating means and gearing whereby said gearing may be arrested independently of the means for actuating it.

15. The combination with a register-operating mechanism, of a motor arranged to be actuated by the weight of the operator, actuating devices for the register-operating mechanism engaging said motor so as to be positively actuated in one direction thereby, and a spring connecting said motor and devices whereby the latter are operated upon the reverse movement of the motor, through the medium of the spring.

16. The combination with a register-operating mechanism, of a motor arranged to be actuated by the weight of the operator in one direction, a spring for moving the motor in the opposite direction, actuating devices for the register-operating mechanism engaging said motor so as to be positively actuated in one direction thereby, and flexible means connecting the motor and said devices, whereby the latter are operated upon the reverse movement of the motor, through the medium of said flexible means.

In testimony whereof I affix my signature in the presence of two witnesses.
